Attorneys

UNITED STATES PATENT OFFICE.

FISHER WRESSELL, OF ALDEN, IOWA.

HOLDER FOR SAFETY-RAZOR BLADES.

Application filed April 7, 1921. Serial No. 459,285.

To all whom it may concern:

Be it known that I, FISHER WRESSELL, a citizen of the United States, residing at Alden, in the county of Hardin and State 5 of Iowa, have invented certain new and useful Improvements in Holders for Safety-Razor Blades, of which the following is a specification.

This invention relates to holders for blades 10 and the primary object of the invention is to provide an improved retainer or holder for safety razor blades which are to be used for any purpose other than shaving, the holder being so constructed as to eliminate 15 the danger and inconveniences incident to the use of safety razor blades for the purpose outlined above.

Another object of the invention is to provide an improved safety razor blade 20 holder which will receive and hold all types of safety razor blades now on the market, and which is so constructed that the blades can be quickly and easily connected to or disconnected from the holder and be held 25 on the holder against accidental displacement or movement.

A further object of the invention is to provide a safety razor blade holder embodying a handle and a blade receiving body 30 member, the handle being so associated with the safety razor blade holder to hold the same against opening movement and the consequent displacement of the razor blade.

A still further object of the invention is 35 to provide an improved safety razor blade holder of the above character, which will be durable and efficient in use, one that is simple and easy to manufacture, and one which can be placed upon the market at a reasonable cost.

With these and other objects in view, the invention consists in the novel construction, arrangement and formation of parts, as will be hereinafter more specifically described, 45 claimed and illustrated in the accompanying drawings, forming a part of this specification, in which drawings:

Figure 1 is a side elevation of the improved safety razor blade holder, showing 50 a safety razor blade therein of the "Gillette" type.

Figure 2 is a similar view showing the safety razor blade therein of the "Gem Junior" or other similar type.

Figure 3 is a detail transverse section

through the holder taken on the line 3—3 of Figure 1.

Figure 4 is a detail transverse section taken through the holder on the line 4—4 of Figure 2.

Figure 5 is a plan view of the blank from which the improved body portion of the razor blade holder is struck.

Figure 6 is a detail edge elevation of the improved safety razor blade holder showing 65 the handle portion thereof in longitudinal section.

Figure 7 is an end elevation of the handle portion of the improved safety razor blade holder.

Referring to the drawings in detail, wherein similar reference characters designate corresponding parts throughout the several views, the letter A indicates the improved holder and B and C the blades which are 75 adapted to be associated therewith.

The holder A includes the blade receiving portion D and the handle portion E.

The razor blade B which is of the "Gillette" type is of the usual configuration and includes the flat body 10 having its opposite edges sharpened at 11, and provided with the openings 12, which are arranged at the longitudinal center thereof. The razor blade B forms no portion of the invention but has merely been shown for illustrating the use of the invention.

The razor blade C as stated, is of the type utilized in the razors of the "Gem Junior" type and includes the blade portion 13, having one longitudinal edge sharpened as at 14, and its opposite longitudinal edge provided with the guard 15.

The portion D for receiving the razor blades B and C is formed from a blank 16 95 shown in Figure 5 of the drawings. This blank is preferably of sheet metal having a certain amount of inherent resiliency and includes the body 17 having the reduced extension 18 formed on its forward end. The 100 opposite ends of the body portion 17 and the extension 18 are provided with shanks 19 and 20, which are adapted to fit in the handle portion as will be hereinafter more fully described.

The shanks 19 and 20 define shoulders 21 which limit the insertion of the shanks 19 and 20 within the handle E which as stated, will be hereinafter more fully described. The body portion 17 has one longitudinal edge thereof provided with 110

a right angularly extending flange 22 which is provided with a ledge 23 which is arranged in substantially parallel relation to the body 17. This flange and ledge forms a 5 guard for one edge of the safety razor blades of the "Gillette" type when utilized in the holder and as a stop for one longitudinal edge of safety razor blades of the "Gem Junior" type. The body 17 and the reduced 10 extension 18 are adapted to lie in substantially parallel relation to each other, and the reduced extension 18 is adapted to be bent along a transverse line so as to overlie the body portion. The longitudinal edges of the 15 body 17 and the extension 18 opposite from the longitudinal edge of the body 17 which is provided with the flange 22 and the ledge 23 can be formed straight or cut into an ornamental shape, as designated by the numeral 20 24. The inner longitudinal edge of the section 18 adjacent to the end which carries the shank 20 is provided with an inwardly extending ear 25, and this extension 18 and the ear 25 and the ledge 23 defines a longitudinally extending slot 26, in which the 25 guard portion 15 of the razor blade C is adapted to fit when blades of this type are utilized with the holder. This body portion 17 is provided with a pair of spaced inwardly extending tits 28, which are adapted 30 to extend into the openings 12 formed in blades B of the "Gillette" type. The pair of tits 28 forms a support for razor blades C of the Gem Junior type.

35 The handle E for the blade holding portion D can be constructed of wood or any preferred material, and has its inner end provided with an inwardly extending polygonal shaped bore 29 in which is adapted 40 to fit the shanks 19 and 20 of the blade receiving portion D. In order to facilitate the clamping action on the shanks, and prevent undue wear on the handle E, an end cap 30 is provided for the handle. This end 45 cap is preferably formed of metal and is provided with a polygonal shaped aperture 31 for the reception of the shank. This aperture 31 is adapted to be placed in direct alignment with the bore 29 in the handle E.

50 In use of the improved razor blade holder, the blade holding portion D proper is removed from the handle portion E and the shanks 19 and 20 are grasped by the fingers so as to spread the reduced portion 18 and the body portion 17. This permits the 55 convenient insertion of a blade B or C in the holder portion proper. If a blade of the "Gillette" type is to be inserted in the holder, one edge is placed underneath the ledge 23 and the tits 28 are inserted in the recesses 12 formed in the blade 10. The body portion 17 and the reduced extension 18 are then permitted to resume their normal position, and the shank portions 19 and 60 20 are inserted in the bore of the handle

E. This firmly holds the body portion 17 and the reduced portion 18 into intimate engagement with the opposite surfaces of the blade and effectively hold the same against accidental displacement.

70 When a blade designated by the letter C of the "Gem Junior" type is to be used with the holder, the guard portion 15 thereof is placed in engagement with the free edge 75 of the ledge 23 and the blade portion is laid on top of the tits 28 and the guard is moved to extend through the slot 26 defined by the inner longitudinal edge of the reduced portion 18, the tongue 25, and the ledge 23. This effectively holds the blade 80 in position against accidental removal.

85 From the foregoing description, it can be seen that an improved holder for safety razor blades has been provided, which will effectively permit the safety razor blade to be used for any and all purposes, such as the sharpening of pencils, the ripping of stitches or the like. The device also forms a novel holder for permitting the ready sharpening 90 of razor blades.

95 Changes in details may be made without departing from the spirit or scope of this invention; but,

I claim:

1. A safety razor blade holder comprising 100 a blade holder portion including a pair of members arranged to engage the opposite sides of the razor blade, the members being connected together at one end, shanks formed on the free ends of the members, an inwardly extending ledge formed on one longitudinal edge of one of the members arranged to receive the cutting edge of one style of razor blade, inwardly extending tits formed on the mentioned member 105 arranged to fit in openings formed in the same style of razor blade, the other member having an inwardly extending notch formed in one of its longitudinal edges, arranged to receive the thickened portion of another style of razor blade, the ledge being adapted to engage the thickened portion 110 of the second mentioned style of razor blade, a handle, and means for connecting the members with the handle.

115 2. A safety razor blade holder comprising 120 a handle having an inwardly extending polygonal bore, an end cap fitted upon said handle having a recess of the same configuration and communicating with said bore, a blade receiving portion including a pair of members arranged to engage the opposite sides of a safety razor blade, the members being connected together at one of their ends, reduced shank portions formed on the 125 ends of the member, an inwardly extending flange formed on one longitudinal edge of one of the members, the other member being reduced in width, inwardly extending tits formed on the first mentioned member,

a laterally projecting ear formed on one longitudinal edge of the reduced member and arranged to engage the flange formed on the longitudinal edge of the other member, and a removable handle member arranged to receive said shanks.

3. As a new article of manufacture, a holder for different types of safety razor blades comprising a pair of companion 10 blade clamping members, means connecting the members together at one end, shanks formed on the opposite ends of said members, a handle for receiving the shanks adapted to hold the members in blade clamp- 15 ing position, one of said members being formed relatively wide and the other rela-

tively narrow, said members having one of their longitudinal edges disposed in parallel alignment, the relatively wide member being extended laterally of the other member, a combined guide and stop flange formed on the laterally extending portion of the relatively wide member, the inner edge of the relatively narrow member being disposed in parallel relation to said flange and forming a shoulder, and a laterally extending lug formed on the relatively narrow portion adjacent to the shank thereof and arranged to engage the guide and stop flange at one end thereof.

20 25 FISHER WRESSELL.
